UNITED STATES PATENT OFFICE.

JOHN STADTHERR, OF GIBBON, MINNESOTA.

IGNITION DEVICE FOR EXPLOSIVE-ENGINES.

No. 855,209.

Specification of Letters Patent.

Patented May 28, 1907.

Application filed February 8, 1907. Serial No. 356,397.

To all whom it may concern:

Be it known that I, JOHN STADTHERR, a citizen of the United States, residing at Gibbon, in the county of Sibley and State of Minnesota, have invented certain new and useful Improvements in Ignition Devices for Explosive-Engines, of which the following is a specification, reference being had to the accompanying drawings.

10 My invention relates to improvements in ignition devices for explosive engines; and an object of my invention is to provide a device of this character which will be self-cleaning, maintaining the surfaces of contact free at all times from soot, rust, burnt carbon, scale and other foreign substances.

Another object of my invention is to provide means for controlling the travel of one of the electrodes with a view to regulating the 20 time of explosion.

A further object of my invention is to provide a device of this character which will be simple in construction, cheap in manufacture and efficient and durable in operation.

25 In the drawings illustrating the principle of my invention and the best mode now known to me of applying that principle, Figure 1 is a longitudinal sectional elevation of my new device; Fig. 2 is a sectional detail 30 showing the electrodes during contact; and Fig. 3 is a detail showing the position of the electrodes at the instant of sparking.

In one end of the explosion chamber or cylinder *a* and insulated therefrom is mounted 35 an electrode cylinder *b* in which is pivotally mounted at *c* the oscillating electrode *d*. Through the stuffing-box *c* passes a rod *f* the lower end of which is connected with the oscillating electrode *d* and the upper end of 40 which is threaded. Upon the latter are screwed the adjusting nut *g* and the lock-nut *h*. Between the nut *g* and the stuffing box *e* is interposed a coil spring *i*.

The slidable electrode *j* enters the explosion chamber from the opposite end thereof 45 and passes through the stuffing-box *k* between which and a collar *m* on the electrode *j* is mounted a coil spring *n*.

One pole of the battery is connected with 50 the walls or casing of the electrode chamber *b* by means of a binding post or screw *o*, while

the other pole is connected with the casing of the explosion chamber *a* by means of the binding post *p*.

While the engine mechanism is not shown 55 herein, it will be understood by all skilled in this art that the slidable electrode is forced into the explosion chamber against the tension of the coil spring *n* by suitable mechanism controlled by the engine shaft.

60 The slidable electrode *j* is shown in Fig. 1 as at the beginning of its inward stroke. As it continues to move inwardly, its chisel-shaped end *q* slidingly engages the chisel-shaped end *q'* of the oscillating electrode *d*, 65 swinging the latter downwardly upon its pivot *e* against the tension of the coil spring *i* and scraping from the surfaces of contact all foreign matter, which insures small electrical resistance and a full current. Fig. 2 70 shows the slidable electrode at the limit of its inward travel.

Under the influence of the coil spring *n* the 75 slidable electrode *j* moves outwardly, during which movement the coil spring *i* holds the chisel-shaped ends *q*, *q'* in scraping contact. Fig. 3 shows the position of the electrode ends at break or the instant of sparking. This instant is determined by the adjustment of the screw *r*, which is held in place by 80 the lock-nut *s* and which controls the travel of the oscillating electrode *d* in an upward direction. By screwing the screw *r* into the electrode chamber *b*, the time of contact will be prolonged and the instant of sparking will 85 be delayed. It will be evident to all skilled in this art that the screw *r* is readily accessible to the engineer at all times and furnishes a quick and ready means of adjustment. Further, the screw *r* serves to keep the oscillating electrode *d* in such a position that it will 90 at all times be engaged by the slidable electrode *j*.

The chisel-shaped ends of the electrodes serve to insure a full contact until the moment of break and thereby a current of great intensity, which at the instant of break results in pronounced arcing.

I claim:

95 In a device of the character described, the combination of a spring-controlled electrode mounted free to oscillate; a slidable electrode

2
which co-operates therewith; an explosion cylinder into which the ends of said electrodes project; and means operable from outside said cylinder to limit the travel of said oscillatory electrode, and thereby to control the time of ignition.

5 In testimony whereof I have hereunto set

my hand at said Gibbon this fifth day of February, A. D. 1907, in the presence of the two undersigned witnesses.

JOHN STADTHERR.

Witnesses:

A. E. FENSKY,
ALBERT L. YOUNG.
